PRODUCTION OF SATURATED HYDROCARBONS

Johan Jacob de Jong, Amsterdam, Netherlands,
assignor to Shell Development Company, San
Francisco, Calif., a corporation of Delaware

No Drawing. Application November 21, 1939, Serial No. 305,498. In the Netherlands November 22, 1938

12 Claims. (Cl. 260—683.4)

This invention relates to the manufacture of branched chain aliphatic hydrocarbons, particularly the production of branched chain paraffins boiling in the gasoline range and having anti-knock properties. It deals with the manufacture of such branched chain paraffins by alkylation of isoparaffins in the presence of sulphuric acid catalyst.

One object of the invention is to extend the life of sulphuric acid catalysts used for the alkylation of isoparaffins. Another object is to provide a new class of alkylating agents which may be reacted with isoparaffins in the presence of sulphuric acid and which offer advantages over the olefines which hitherto have been the only agents used. Still another object is the more efficient and economical use of olefines as starting materials for the alkylation of isoparaffins. It is a further object to reduce the power requirements and distillation expense when using as starting material olefines admixed with normal paraffins.

Heretofore the only commercially practical method of alkylating isoparaffins has been by reaction with olefines in the presence of concentrated sulphuric acid as described for example in copending application Serial No. 150,544 filed June 26, 1937. This method as preferably carried out with the hydrocarbons in the liquid phase and using an excess of isoparaffin to olefine has been highly successful. It nevertheless has certain undesirable features which it is an object of the present invention to improve upon. Thus, for example, in the alkylation of isobutane with propylene containing propane such as is available from the cracking of petroleum hydrocarbons, the excess isobutane becomes contaminated by propane and extra distillation expense is necessary if the isobutane is to be profitably reused in the process. Also the necessity of compressing and maintaining liquid such low boiling hydrocarbons involves high power costs and makes necessary more expensive equipment capable of withstanding the higher pressures involved. These disadvantages are avoided by the process of the present invention which also makes it feasible to utilize the olefine content of olefine-poor refinery gases for the alkylation of isoparaffins.

It has been found that alkyl esters of polybasic mineral acids, such, for example, as sulphuric acid can be reacted with branched chain paraffins in the presence of concentrated sulphuric acid to form alkylation products of the isoparaffin. Based upon this discovery a commercially practical method which offers many advantages over the alkylation with an olefinic feed has been

developed. Either neutral esters, e. g. dialkyl sulphates, or acid esters, e. g. mono-alkyl sulphates or mixtures comprising both types of esters may be used for alkylating isoparaffins in accordance with the invention. It may be that the reaction with neutral alkyl esters involves acid alkyl esters as intermediates but there are special advantages in using the neutral esters and this important modification of the invention as carried out with dialkyl sulphates, for example, will be described first.

Examples of neutral sulphuric acid alkyl esters used according to the invention, which are conceivable as being derived from primary and secondary as well as tertiary alcohols and which may also be used as mixtures, are for example: diethyl sulphate, dipropyl sulphate, di-isopropyl sulphate, di-normal butyl sulphate, di-isobutyl sulphate, di-secondary butyl sulphate, di-tertiary butyl sulphate, dipentyl sulphates, dihexyl sulphates, diheptyl sulphates, di-octyl sulphates (e. g. the neutral sulphuric acid ester of di-isobutene) and didodecyl sulphates (e. g. the neutral sulphuric acid ester of tri-isobutene). Use may also be made of mixed neutral sulphuric acid alkyl esters containing two different alkyl groups in the neutral sulphuric acid ester. Preferably neutral sulphuric acid alkyl esters of branched or non-branched alkenes are used but neutral esters of cyclic olefines as dicyclohexyl sulphate and the like may also be employed. Suitable methods for preparing dialkyl sulphates which may be used in the process of the invention are described for example in U. S. Patents 1,854,581 and 1,967,399. The neutral sulphates may be used in the crude form in which they are initially obtained or in admixture with other substances or may advantageously be purified, for example by extraction with cold water or other suitable solvent for acid alkyl sulphates, prior to use in the alkylation.

Examples of isoparaffins which may be reacted with such neutral sulphuric esters are isobutane, isopentane, 2-methyl pentane, 3-methyl pentane, 2,3-dimethyl butane, isoheptanes and the like, including for example, higher boiling paraffins obtained in the alkylation process. It is further unnecessary to cause pure isoparaffins to react with the neutral sulphuric acid alkyl esters, it being also possible to start from mixtures containing isoparaffins, e. g. mixtures of isoparaffins and normal paraffins.

The neutral sulphate esters are substantially non-reactive with such isoparaffins in the absence

of catalysts but react in the presence of at least an equal molecular amount and more preferably a substantially larger amount of concentrated sulphuric acid. The best results are obtained with sulphuric acid of 90% to 100% concentration at reaction temperatures between about -10° and +50° C., however somewhat higher or lower acid concentrations and/or temperatures may also be used, the optimum conditions depending upon the particular neutral ester or esters involved and the isoparaffin or isoparaffins being reacted therewith. Whatever the temperature used it is preferred to operate with the reactants in the liquid phase but either or both may also be used in the gaseous state and whether or not the preferred liquid phase method of reaction is employed, the process may, if desired, be carried out in the presence of materials not participating in the reaction which materials may be gases, e. g. hydrogen, methane, nitrogen or carbonic acid, or liquids as non-reactive hydrocarbons, carbon tetrachloride, etc.

It is desirable that at least two, and preferably three to six or more, molecules of isoparaffin should be present to each molecule of neutral sulphuric acid alkyl ester. One may also use less than two molecules of isoparaffin per molecule of neutral sulphuric acid alkyl ester. An excess of isoparaffins is, however, favorable to a longer activity of the sulphuric acid. It is also desirable in order that full advantage be derived from the isoparaffin:ester ratio used that the alkyl ester be brought rapidly into uniform intimate contact with the isoparaffin and catalyst. To this end it is helpful to premix the alkyl ester with isoparaffin before contacting it with the catalyst acid which preferably is also premixed with isoparaffin. When using neutral esters they may be applied advantageously as a solution in the isoparaffin to be alkylated which solution is fed into a suspension of catalyst acid and isoparaffin-containing hydrocarbon.

A simple method of operation comprises feeding the isoparaffin and alkyl ester into an intensively stirred mixture of isoparaffins and sulphuric acid in which the temperature may be controlled by circulation of a suitable cooling agent or by evaporation of a part of the reaction mixture, e. g. a part of the excess isoparaffin. In batchwise operation the stirring may be discontinued at the end of the reaction period which preferably is extended beyond the time required for addition of the alkyl ester after which the mixture may be stratified in the same or another suitable vessel whereupon the hydrocarbons separate as a top layer which may be separated and the bottom layer of sulphuric acid re-used for further alkylation, preferably after separation of a volume at least equivalent to the increase in the acid resulting from the reaction and more preferably a larger amount although most preferably still a minor proportion of the total acid, which excess may be replaced by fresh acid while the withdrawn acid may be used at least in part for the preparation of the alkyl sulphate or sulphates being reacted. The separated top layer of hydrocarbon, preferably after water and/or caustic washing or other suitable treatment for removal of acid and/or esters if present therein (compensation for which should be made when adding fresh catalyst acid) may be fractionated and a water-white sulphur-free alkylation product with a bromine number equal or practically equal to zero and entirely or substantially consisting of isoparaffins of high anti-

knock value, obtained. The excess isoparaffin may be reused in the alkylation process.

Intermittent or continuous methods of operation may also be used and in any case it is desirable to mechanically circulate dispersed reaction mixture, for example, by a centrifugal pump taking suction at a suitable point in the reactor and discharging back into the bottom or vice versa. Most preferably the invention is carried out continuously by the method described and claimed in copending application Serial No. 245,714 filed December 14, 1938, by continuously feeding alkyl ester and isoparaffin into a circulating stream of a dispersion of catalyst acid and reacted hydrocarbon mixture comprising the isoparaffin to be alkylated, withdrawing a part of the circulating mixture for separation of reaction product and returning at least a part of the unreacted isoparaffin and a suitable proportion of the catalyst acid to the circulating stream. Still other methods of carrying out the alkylation reaction of the invention may be used. Multi-stage operation with the alkylation units in series employing either concurrent or countercurrent flow of reactants and catalyst acid with feed of alkyl sulphate to one or several or all of the units or other suitable arrangements may be employed.

Whatever the procedure adopted for carrying out the alkylation it is advantageous to use polyalkyl esters of polybasic mineral acid such, for example, as dialkyl sulphates, di- or tri-alkyl phosphates, dialkyl borates and the like as feed to the alkylation unit. When employing sulphate esters as the alkylating agent, sulphuric acid from the alkylation stage may be used for the preparation of the ester or esters. Thus a part of the acid from the stratifier of the alkylation unit may be used to react with olefines to form the desired ester. For the preparation of polyalkyl esters it is advantageous to contact the olefine and acid in the proportions of about two mols of olefine per mol of acid. Where cracked fractions of petroleum hydrocarbons are used as the source of the olefines the dialkyl sulphates formed will be present for the most part in the upper layer of hydrocarbon obtainable by stratification of the reacted mixture. Such upper layer will also contain the bulk of the polymers if any are formed during the reaction. This upper layer, preferably after separation of any normally gaseous hydrocarbons present may be used as the alkylating agent in the process of the invention with or without separation of the polymers. While the polymers may be successfully reacted with isoparaffins along with the alkyl esters and appear to generally give the same type of products it is preferred to operate with minimum polymer formation. To this end it may be desirable when using mixtures of olefines of different orders of reactivity to contact the acid with the least reactive olefine first and use the reaction product to contact the mixture containing the more reactive olefine. Thus, for example, a fraction containing iso- and normal butylenes may be contacted with an absorption product of normal butylenes in withdrawn alkylation acid and the residual olefines used to form the absorption product employed. Alternatively the more reactive olefines may be first reacted with more dilute acid. It may be advantageous to carry out the entire olefine reaction with acid from the alkylation unit which has been suitably diluted to reduce undesirable side reactions. Such dilute acid tends to favor formation of larg-

er proportions of acid sulphates but these may be converted to neutral esters by further reaction with more olefine, preferably after removal of any neutral esters initially formed. The separation of neutral esters may be effected by extraction with a suitable solvent advantageously the isoparaffin to be alkylated. In any case the concentration of acid, temperature and proportion of olefine to acid should be adjusted in accordance with the nature of the olefine or olefines and polybasic mineral acid involved so that the desired ester is produced. Thus, for example, quite high temperatures are useful when preparing esters from ethylene while as a general rule higher secondary olefines are more advantageously treated at lower temperatures and tertiary olefines at still lower temperatures although with olefines of six or more carbon atoms per molecule the differences between secondary and tertiary olefines are of less importance. The conditions of alkylation with the alkyl esters are roughly analogous to those required for absorption of the corresponding olefine in the sense that those which require higher temperatures for their rapid formation are best reacted with isoparaffins at higher temperatures than the more easily formed esters of olefines. Thus, for example, while di-isopropyl sulphate reacts only slowly with isobutane or isopentane at temperatures below 0° C. and appears to have an optimum reaction temperature between about 15° and 25° C., di-secondary butyl sulphate reacts at temperatures as low as -10° C. although better results are obtained between about 0° and 15° C. By using ester mixtures or the corresponding mixed esters alkylations with the less reactive alkyl groups may be more easily carried out than by the use of such esters alone.

Without implying any limitation on the invention the following explanation is offered for the more advantageous results, particularly with respect to catalyst life, obtainable by the use of polyalkyl esters of polybasic inorganic acids as feed to the alkylation unit instead of the corresponding olefines or mono-alkyl esters. Although di-

the advantageous results which may be obtained by the method of the invention when using di-alkyl sulphates as feed to the alkylation unit.

Example I

5 120 parts by weight di-isopropyl sulphate were introduced in about 1½ hours during intensive mechanical stirring at 20° C. into a reaction vessel containing 95 parts by weight isopentane and 98 parts by weight sulphuric acid of 98% concentration. The mixture, after having been stirred for another half hour, was allowed to stratify whereby a colourless top layer separated off in a quantity of 145 parts by weight, with a bromine 10 figure=0 and containing 80% hydrocarbons with an octane number=93 and boiling between 50 and 200° C.

15 The bottom layer consisted of 167 parts by weight and contained 92.5% sulphuric acid.

20 In an experiment carried out under approximately the same conditions (98% H₂SO₄ at 20° C.) it was found that isopentane did not react with diethyl sulphate but by using higher temperatures of the order of about 25° to 40° C. the reaction 25 may be made to go readily giving equivalent yields of alkylation products the principal fraction of which boil in the isoheptane range.

Example II

30 Di-isopropyl sulphate was reacted with isobutane in a pressure vessel equipped with a high speed stirrer driven by an electric motor enclosed in the same casing and having inlet lines for isobutane and dipropyl sulphate mixture and for sulphuric acid, the former feeding into the bottom and the latter at a higher level but below the motor. The apparatus was also provided with outlet lines at the same levels as the inlet lines and was surrounded by a water bath kept agitated with air which maintained a reaction temperature of 20° C. The same charge of catalyst acid was successively used for the reaction of five charges of isobutane and di-isopropyl sulphate each for a period of four hours under the following conditions and with the following results:

Concentration of H ₂ SO ₄ in the catalyst at start	Mols of di-isopropyl sulphate per mol of isobutane in feed	Weight ratio of catalyst phase to di-isopropyl sulphate fed	Increase in weight of catalyst layer	Kilograms of stabilized hydrocarbon obtained per kilogram of catalyst acid used	Yield of de-butanized alkyl product as percent by wt. of the propylene intake
Percent					
98	1.01	1.76	Percent	0.89	Percent
93 1/2	1.05	2.8	58	0.85	262
92 1/2	1.1	3.84	37.2	0.83	276
90	1.1	4.74	26.4	0.83	279

¹ Not determined.

alkyl sulphates, for example, are more stable than the corresponding mono-esters in the presence of sufficient concentrated sulphuric acid they appear to react rapidly with isoparaffins under suitable conditions, the reaction going substantially to completion with the alkylation of two molecules of isoparaffin per molecule of di-alkyl sulphate. As a result it may be that there is less opportunity for the catalyst acid to accumulate sufficient alkyl acid sulphate or for such sulphate to remain in contact with the acid long enough for undesirable side reactions such as hydro-polymerization and the like leading to deactivation of the catalyst acid through accumulation of organic material therein, to take place. However that may be the following examples show

60 The reaction product had a very satisfactory volatility, 90% boiling below 160° C. and having a clear octane number of 88 which was increased to 99 by addition of 2 ml. of tetraethyl lead per imperial gallon. The remarkably high yield, 65 above the theoretical of 238%, may be accounted for by the possible presence of some di-hexyl sulphate formed from polymers produced during absorption of the propylene in the preparation of the di-isopropyl sulphate.

Example III

Gaseous propylene containing hydrocarbon was fed into sulphuric acid which was being vigorously stirred. The reaction vessel was cooled by an acetone-carbon dioxide mixture kept at -15° C.

With 447.5 grams of 100% H_2SO_4 and a feed rate of approximately 0.1-0.4 gram of propylene per gram of H_2SO_4 per hour, 1.90 mols of propylene were absorbed per mol of H_2SO_4 and the product had the following composition:

	Per cent
Free acid	1.5
Mono-isopropyl sulphate	15.5
Di-isopropyl sulphate	79.0

The product was reacted with isopentane using 98 grams of 98% H_2SO_4 and 95 grams of isopentane in a stirred flask cooled by a water bath which maintained a reaction temperature of 20° C. The di-isopropyl sulphate was added slowly to the mixture which was stirred at 1500 R. P. M. After addition of 120 grams of ester mixture at a rate of 0.18 gram of C_3H_6 per gram of catalyst per hour and a total reaction time of 2½ hours, the mixture was stratified and 167 grams of acid layer analyzing 93% free H_2SO_4 was separated from 138 grams of hydrocarbon layer.

The alkylation products were found to be predominantly branched chain octanes.

A corresponding experiment in which the acid was added to a mixture of isopentane and diisopropyl sulphate gave less satisfactory results.

While reaction with dialkyl sulphates has been emphasized because of the many operating advantages obtainable by the use of this type of polyalkyl ester, particularly the fact that a part, usually of the order of about one-fourth to one-twelfth, preferably about one-tenth, of the alkylation acid may be recycled to the olefine treatment stage for the formation of the esters and no problem of separation of acids is involved, esters of other polybasic inorganic acids corresponding to any of the sulphates described by way of example may also be used. Thus, for example, methyl ethyl phosphate, dipropyl phosphate, dipropyl secondary butyl phosphate, dimethyl isopropyl borate and the like may be used in the same manner as sulphate esters provided suitable adjustment of the operating conditions is made. The polyalkyl esters may be produced from the corresponding alcohols or alcohol mixtures or by any other suitable manner.

There is some advantage, particularly in respect to simplicity of operation, to be derived from the use of feeds to the alkylation unit containing alkyl acid esters particularly mono-alkyl sulphates. These may readily be formed by simple absorption of the corresponding olefine in sulphuric acid, preferably sulphuric acid obtained from the alkylation step of the process. Particularly when using recycled alkylation acid from alkylation stage there may be polymers formed during the olefine absorption but these, together with any dialkyl sulphates contained therein may be fed to the alkylation unit, preferably after removal of normal paraffins therefrom, along with the alkyl acid sulphate-containing absorption product and all three reacted with isoparaffin. Suitable methods for carrying out the absorption of olefines are described, for example, in U. S. Patents 1,955,873 and 2,106,521. Where mixtures of tertiary and secondary olefines are being used the absorption procedure of U. S. Patent 2,060,143 may be advantageously used with or without the dilution step between absorption stages described therein since any polymers formed may also be used for alkylation. U. S. Patents 1,938,177, 2,007,159 and 2,007,160 describe alternative methods of treating olefine

mixture to obtain polymers and alkyl esters of polybasic mineral acids which may be alkylated in accordance with the present invention. The alkyl esters of olefine polymers described in U. S. Patent 2,139,394 may also be used for effecting the alkylation.

It is generally desirable to carry out the olefine absorption using a molecular excess of olefine to acid and preferably about two mols of olefine per mol of acid. While the best temperature for olefine absorption varies with the olefine being used it is usually advantageous to employ temperatures which are lower than those used for the subsequent alkylation when using acid of the same concentration in both steps, e. g. when carrying out the absorption with acid from the alkylation unit. In general the alkylation with monoalkyl esters may be carried out in a manner similar to those previously described for the reaction with polyalkyl esters.

The following example shows a typical application of the invention to the alkylation of iso-paraffins with alkyl acid sulphates.

Example IV

Propyl acid sulphate was prepared by agitating a weighed quantity of a propane propylene fraction containing 80.7% propylene with 100% H_2SO_4 in a stirred mixer. After completion of the absorption the charge was drained from the mixer which was then recharged with H_2SO_4 and isobutane. The isopropyl acid ester was then added dropwise to a H_2SO_4 -isobutane mixture at 10° C. and the stirring continued for some time. The acid phase from the alkylation reaction was analyzed and the hydrocarbon phase was stabilized and distilled.

Formation of ester:

40	Acid charge (100% H_2SO_4)	grams	153
	Propylene charge (80.7%)	do	72
	Recovered acid phase	do	202
	Initial acidity as per cent H_2SO_4		43.6
	Per cent free H_2SO_4		17.6
	Total acidity as per cent H_2SO_4		70.7

Reaction of ester with isobutane:

45	Acid charge (100% H_2SO_4)	grams	365
	Isobutane (99.5%)	do	200
	Product from ester formation	do	158
	Product (acid phase)	do	453
50	Initial acidity as per cent H_2SO_4		96.5
	Per cent free H_2SO_4		95.8
	Total acidity as per cent H_2SO_4		96.9
	Product (hydrocarbon phase)	grams	220
	Debutanized product	do	77.4

By a similar procedure using an absorption product of secondary butylenes in sulphuric acid alkylate yields of the order of 200% to 225% may be obtained from isopentane, with a sulphuric acid catalyst consumption no greater than that obtainable by the direct use of the olefine.

One particularly advantageous method of applying the reaction of alkyl acid sulphates in accordance with the invention is in the regeneration of alkylation acid which may advantageously be effected by agitating sulphuric acid which has been used for the alkylation of iso-paraffins, whether with olefines or alkyl esters, with an isoparaffin substantially free of olefines. Either the same, or another, isoparaffin may be used for the reaction which may be carried out at the same, or preferably a somewhat higher, temperature than was used for the original alkylation. In this way the alkyl acid sulphate content of the acid may be reacted and not only may

additional valuable isoparaffins be recovered but also the concentration of the acid and its effectiveness in catalyzing further alkylation may be increased.

Still other variations may be made in the process which is not limited to the details described only by way of illustration but only by the appended claims.

I claim as my invention:

1. A process for producing gasoline boiling hydrocarbons from normally gaseous hydrocarbons containing an olefine which comprises contacting said hydrocarbon with sulphuric acid of 90% to 100% concentration on a hydrocarbon free basis in the proportion of at least two mols of olefine per mol of sulphuric acid under conditions at which a dialkyl sulphate of said olefine is formed, separating the reaction mixture into a hydrocarbon phase containing said dialkyl sulphate and an acid phase, removing unreacted normally gaseous hydrocarbon from said separated hydrocarbon phase and contacting the dialkyl sulphate with a dispersed mixture of an isoparaffin and sulphuric acid of 90% to 100% concentration, maintaining in the reaction mixture at least three mols of isoparaffin and at least one and one-half mols of sulphuric acid per mol of dialkyl sulphate at a temperature between -10° C. and +40° C. at which alkylation of said isoparaffin by said dialkyl sulphate takes place, stratifying the reacted mixture into a hydrocarbon phase containing the alkylation product and an alkylation acid phase, separating a minor part of the latter and supplying it to said olefine contacting stage and returning a larger part to said isoparaffin alkylation.

2. A process for producing gasoline boiling hydrocarbons from isobutane and a normally gaseous olefine which comprises contacting hydrocarbon containing said olefine and sulphuric acid of at least 90% concentration on a hydrocarbon free basis which has been employed for the alkylation of isobutane in the proportion of at least two mols of olefine per mol of sulphuric acid under conditions at which a dialkyl sulphate corresponding to said olefine is formed, diluting the reaction product with sufficient water to cause separation of a phase containing said dialkyl sulphate substantially free from alkyl acid sulphates, admixing the separated dialkyl sulphate with a molar excess of isobutane in the liquid phase and feeding the resulting mixture into a dispersion of liquid isobutane and sulphuric acid of 90% to 100% concentration on a hydrocarbon free basis and correlating the amount and concentration of the acid, the reaction temperature and the proportion of dialkyl sulphate to isobutane to effect alkylation of the isobutane as the principal reaction in the process.

3. A process of alkyllating isobutane, which comprises contacting isobutane and a dialkyl sulphate in the proportions of at least three molecules of isobutane per molecule of said sulphate in the presence of sulphuric acid of 90% to 100% concentration on a hydrocarbon free basis at least equivalent to one mol of acid per mol of said sulphate at a temperature between -10° C. and +40° C. at which alkylation of isobutane takes place.

4. A process of alkyllating an isoparaffin which comprises contacting said isoparaffin and a neutral polyalkyl ester of a polybasic mineral acid with concentrated sulphuric acid and correlating the amount and concentration of sulphuric acid, the reaction temperature and time, and the pro-

portion of isoparaffin and ester to effect alkylation of the isoparaffin by said ester as the principal reaction in the process.

5. The method in the alkylation of a low-boiling isoparaffin with a low boiling olefin utilizing an olefinic feed stock containing a more reactive tertiary olefin and an isomeric less reactive secondary olefin, which comprises separately converting the more reactive olefin and the less

10 reactive olefin to the corresponding dialkyl sulfates, reacting the dialkyl sulfate from the more reactive tertiary olefin with a low boiling isoparaffin in the presence of concentrated sulphuric acid of alkylation strength in a reaction zone maintained under less drastic alkyllating conditions, and alkyllating an isoparaffin with the dialkyl sulfate from the less reactive secondary olefin with concentrated sulfuric acid of alkylation strength in another reaction zone maintained under more drastic alkyllating conditions.

6. The method in the alkylation of a low boiling isoparaffin with a low boiling olefin utilizing an olefinic feed stock containing a more reactive olefin and a less reactive olefin, which comprises 15 separating the more reactive olefin from the less reactive olefin by selective conversion of the former to the corresponding dialkyl sulfate, alkyllating an isoparaffin with said dialkyl sulfate, then converting the less reactive olefin to a dialkyl sulfate and alkyllating an isoparaffin therewith in the presence of concentrated sulfuric acid at a higher temperature.

7. The process which comprises forming a mixture of a polyalkyl ester of a polybasic inorganic acid and the corresponding acid, extracting said polyalkyl ester from said acid with an isoparaffin and contacting the extract with concentrated sulfuric acid under conditions at which alkylation of said isoparaffin is effected.

8. A process of alkyllating an isoparaffin which comprises adding a substantial amount of a pre-formed dialkyl sulfate to a molal excess of said isoparaffin in the presence of concentrated sulphuric acid and correlating the amount and concentration of sulphuric acid, the reaction temperature and time, and the proportion of isoparaffin and dialkyl sulfate to effect alkylation of the isoparaffin by said dialkyl sulfate as the principal reaction.

9. The process which comprises forming a mixture of a dialkyl sulfate and sulfuric acid, extracting said dialkyl sulfate from said sulfuric acid with an isoparaffin, and contacting said extract with concentrated sulfuric acid under conditions at which alkylation of said isoparaffin is effected.

10. The process which comprises forming a mixture of di-isopropyl sulfate and sulfuric acid, extracting said di-isopropyl sulfate from said sulfuric acid with an isoparaffin, and contacting said extract with concentrated sulfuric acid under conditions at which alkylation of said isoparaffin is effected.

11. The process which comprises absorbing 65 propylene in sulfuric acid so as to form a mixture of di-isopropyl sulfate and sulfuric acid, extracting said di-isopropyl sulfate from said sulfuric acid with isopentane, and contacting the extract with concentrated sulfuric acid under conditions at which alkylation of the isopentane is effected.

12. A process of alkyllating an isoparaffin which comprises reacting said isoparaffin with a neutral alkyl borate in the presence of concentrated sulphuric acid under alkyllating conditions.
